UNITED STATES PATENT OFFICE.

NORMAN GROSS, OF HARTFORD, CONNECTICUT.

GARMENT.

1,213,181.

Specification of Letters Patent. Patented Jan. 23, 1917.

Application filed January 2, 1915. Serial No. 270.

To all whom it may concern:

Be it known that I, NORMAN GROSS, a citizen of the United States, residing at 25 Winthrop street, in the town of Hartford, in the county of Hartford and State of Connecticut, have invented certain new and useful Improvements in Garments, of which the following is a specification.

My invention relates to a device of the class specified which has features of novelty and advantage.

Though not confined to any particular class of garments it is preferably used in connection with sweaters and is more particularly and preferably described as sweater with a detachable collar.

Figure 1 is a view of the sweater with collar attached and turned down. Fig. 2 is a view of the sweater without the collar, showing the neck. Fig. 3 is an inside view of the sweater with the collar turned up. Fig. 4 is an outside view of the sweater with the collar turned up. Fig. 5 is an outside view of the sweater with the collar turned down. Figs. 6, 7 and 8 are separated portions of the collar. Figs. 9 and 10 are corresponding portions of the fastener.

Referring now more particularly to the drawings, the neck of the sweater (1) is so constructed that a collar may be affixed thereto, detachable or otherwise. As is shown in Fig. 1 any method of so attaching and detaching the collar may be used but I prefer that type of fasteners which may be easily separated so that the collar may be removed without taking off the sweater. For this the preferable type of fasteners is what might be called the glove fastener, as shown in Figs. 9 and 10. By employing these fasteners the collar, as stated, may be easily removed by grasping one end and pulling; each fastener being thereby disengaged without the necessity of releasing each one by hand.

It will be noticed that the fasteners are preferably disposed along the extreme lower margin of the collar, and also that this extreme lower margin approaches more nearly to a straight line than the margin of the neck (1). Consequently these fasteners are so placed preferably on the neck that at the

back they are close to its lower margin and when extending around the side toward the front they tend to approach its upper margin. I find this method very preferable for maintaining a correct fit of the sweater.

It will also be noticed that the collar is so connected that one portion of the fastener is on the inside of the neck and its corresponding portion on the outside of the collar, thus preventing any portion of the fastener from being exposed to view while the collar is in place. Furthermore I preferably desire that that portion of the fastener disclosed in Fig. 10 should be attached to the neck so that when the collar is removed this fastener will cause no inconvenience to the body of the wearer having the least possible projection.

I prefer to construct the collar generally in the manner shown and I believe that this collar can be made to best advantage in the following way, that is, by constructing it of several sections, although I do not confine myself particularly to that.

The collar I construct preferably in several sections, that in the drawing being composed of three. Each one of these sections is knitted separately, as for instance that portion shown in Fig. 7. The knitting is begun at the top and extends toward the edge 10. In like manner those portions shown in Figs. 6 and 8 are knitted, beginning with the top, 13 and 6 respectively, and ending at 16 and 8. In this way the only portions of the collar which are not selvaged are those at 16, 10 and 8. There is thus produced a collar having the major portion selvaged. Furthermore, the edges 12, 13, 9 and 6 are sewed together as loosely or as tightly as you may desire and a very desirable seam is thereby produced. The hinging or swinging motion which takes place at the seams causes the collar to fit much more closely. The seams 18 and 17 are generally so disposed as to extend from the neck outward along the top of the shoulders causing the collar to hinge at that point.

Claim:

A sweater collar comprising an intermediate section and approximately triangular end sections, the side edges of the intermediate section converging inwardly and

with the bottom edge being selvaged, the end sections being selvaged along their inner and bottom edges and the selvaged inner edges of the end sections being secured respectively by stitching to the selvaged sides of the intermediate section.

In testimony whereof I affix my signature in presence of two witnesses.

NORMAN GROSS.
